UNITED STATES PATENT OFFICE.

JAMES G. NOLEN, OF NEW YORK, N. Y.

YIELDABLE SUPPORT FOR PHONOGRAPH RECORDS.

Application filed September 29, 1921. Serial No. 504,227.

To all whom it may concern:

Be it known that I, JAMES G. NOLEN, a citizen of the United States, residing in New York, in the county of New York and State 5 of New York, have invented certain new and useful Improvements in Yieldable Supports for Phonograph Records, of which the following is a specification.

This invention relates to sound or tone improving devices for holding or supporting phonograph record disks for rotation with a turntable, and has for one object to provide a sound improving means which does not require for its use any change in the customary record disk or in the turntables for revolving the disks, or in the disk needles.

Another object is to provide a sound modifier whereby is afforded effective or full needling of the sound waves of a record disk 20 by the needle, representing coarser vibrations or brilliant passages, without chattering or blasting vibrations.

In my invention, the record disk is supported on the turntable upon yielding bosses 25 or nibs; these bosses or nibs being arranged on the face of the sound modifier around the axis thereof, the disk being rotated by the transverse frictional torque of these bosses or nibs. When the disk reaches the parts of 30 the sound waves forming the deeper portions of the grooves, there is resistance and momentary retardation of the rotative movement of the record disk relative to the rotative movement of the turntable, and during 35 such momentary retardation opportunity is afforded for the needle to descend into or engage the full depth of the deeper sound waves, whereby proper or full needling of the sound waves carrying grooves of deep 40 amplitude, representing coarser vibrations or brilliant passages of the record, is permitted. By this arrangement I obviate the tendency of the needle to jump from the crest or apex of one sound wave to the adjacent inclined 45 side of the next sound wave without entering or engaging the portion of the sound wave between said apex and inclined side, thereby to prevent the sound represented by such skipped or omitted portion of the 50 wave from being altogether lost or only improperly reproduced.

In the accompanying drawings, which show one of many possible embodiments of my invention, Figure 1 is a front elevation 55 of a phonograph cabinet, partly broken

away to show my sound modifier and a record disk operatively supported thereby on the turntable of the phonograph mechanism.

Figure 2 is a perspective view of my sound modifier. 60

Figure 3 is a radial sectional view of my sound modifier, the sound modifier being shown operatively carried on the turntable of a phonograph mechanism and supporting a record disk. 65

Figure 4 is a fragmental view showing the sound modifier in radial section and the disk and turntable in edge elevation.

Figure 5 is a detail perspective view of one of the bosses or nibs. 70

Figure 6 is a diagrammatic sectional view on an enlarged scale of one of the bosses or nibs, showing the zone of resilient or yieldable support of the boss or nib.

Similar reference characters denote similar parts throughout the several views. 75

My sound modifier comprises a plate A of aluminum disk record stock, or any suitable metal or material, preferably of disk shape, somewhat less in diameter than a customary record disk, the plate or disk A being provided at its center with an aperture 10 for centering the plate or disk A upon the revoluble post P carrying the phonograph turntable T. The plate or disk A 80 has a smooth upper and under surface.

The plate or disk A is provided on its upper side with bosses or nibs 12 and 13, the bosses or nibs 12 being spaced apart and preferably arranged in a circle of less diameter than the plate or disk A around the periphery of the plate or disk A, the bosses or nibs 13 being spaced apart and preferably arranged around the aperture 10 in a smaller circle or cluster than the circle of bosses or nibs 12, the diameter of this smaller circle or cluster as I have found in practice, preferably being from two to two and one-half inches on a plate or disk A suitable for use with a record disk of the usual diameter, or substantially one-fifth the diameter of the disk, for the most efficient distribution of support. 90

The bosses or nibs 12 and 13 are made of soft rubber, for instance, Pará gum, and 105 preferably have cylindrical stems 14 which are cupped or hollowed out at their upper ends 15, and terminate in thin or fine peripheral edges 16, which engage the under side of the record disk and by transverse 110

torque rotate the disk, the cupped portions of the bosses as shown at $x-x$, Fig. 6, constituting zones of resilient or yieldable support for the record disk.

5 The bosses or nibs 12 and 13 are secured to the plate or disk A in any suitable manner, as by the stems 14 and securing heads 17 shown, which are pressed into mouthed apertures 18 of the plate or disk A and retained therein by the elasticity of the stems and heads.

The plate disk A is centered by means of the aperture 10 on the revoluble post P with which the turntable T revolves, the turntable having the usual frictional or frictional upper surface of felt F or similar material with which the under surface of the plate or disk A engages for rotation with the turntable.

20 In operation, the plate or disk A is placed over the post P, and the record disk D is placed over the plate A, the bosses or nibs 12 and 13 supporting the record disk, the engagement of the cupped ends 15 and the 25 transverse torque of the bosses or nibs 12 and 13 causing the record disk to revolve with the plate or disk A. When during the rotation of the record disk the disk needle N enters those parts of the record groove 30 comprising waves of great amplitude, it causes a very short moment of retardation of the record disk relative to the rotation of the turntable, during which retardation the disk needle, due to the zones of yieldable 35 support of the bosses, is afforded opportunity to enter or engage fully and properly the record wave for the entire length thereof. The moment of retardation is short, usually lasting less than a wave length or at 40 best very few vibrations, so that no lowering of the musical tone is noticeable.

In practice it is found that my invention practically entirely obviates unpleasant chattering and blasting sounds ordinarily 45 produced by waves of deep, or great, amplitude of the coarser and lower notes. This is a great improvement as it prevents the production by the diaphragm of such unpleasant sounds, and also prevents their communication to other parts of the phonograph.

50 Having thus described my invention it should be understood that there may be modifications thereof and variations therein without departing from the spirit of the invention or exceeding the scope of the appended claims.

What I claim and desire to protect by Letters Patent is:—

1. A record support comprising, a base member, and a plurality of cupped projections extending upwardly from the base member, said projections constituting zones of yieldable support for rotation of a record by a phonograph turntable. 60

2. A record support comprising, a base member, and a plurality of cupped projections thereon of resilient material extending above the surface of base member and providing zones of yieldable support for rotation of a record disk by a phonograph 70 turntable. 65

3. A record support comprising, a base member, and a plurality of cupped projections providing zones of yieldable support for rotation of a record disk by a phonograph turntable, the projections being operatively secured in openings through the base member and extending above the surface of the base member. 75

4. A record support comprising, a base member, and a plurality of cupped projections of resilient material providing zones of yieldable support for rotation of a record disk by a phonograph turntable, the projections being operatively secured in openings through the base member and extending above the surface of the base member. 80

5. A record support comprising, a base member, and a plurality of up-standing projections of resilient material thereon, each projection having a body portion cupped at one of its ends for providing a zone of yieldable support for rotation of a record disk by a phonograph turntable, the body portion having at its opposite end a head for operatively securing the projection in an opening through the base member. 90

6. A record support comprising, a base member, and a plurality of up-standing projections of resilient material thereon, each projection having a body portion cupped at one of its ends for providing a zone of yieldable support for rotation of a record disk by a phonograph turntable, the body portion having at its opposite end a laterally extending head for operatively securing the projection in an opening through the base member. 100
